UNITED STATES PATENT OFFICE.

OLIVER THORN, OF LONDON, ENGLAND.

DESIGN FOR A GUN-CARRIER.

SPECIFICATION forming part of Design No. 33,645, dated December 4, 1900.

Application filed August 11, 1900. Serial No. 26,655. Term of patent 7 years.

To all whom it may concern:

Be it known that I, OLIVER THORN, a subject of the Queen of Great Britain and Ireland, residing at London, England, (and whose post-office address is No. 19 Great Portland street, Oxford street, London, England,) have invented and produced a new and original Design for a Gun-Carrier, of which the following is a specification.

10 My invention relates to a new and original design for a carrying attachment for cycles; and it consists of the design embodying the essential characteristics herein described and shown in the accompanying drawings.

15 In the accompanying drawings, Figure 1 represents a perspective view of the attachment embodying my design. Fig. 2 represents a side elevation of the same. Fig. 3 represents an elevation as seen from the right 20 in Fig. 2, and Fig. 4 is a bottom plan view.

A represents a U-shaped member which is slightly shorter at one side, as seen in Figs. 1 and 2, and has an inclined bottom, as seen most clearly in Fig. 3.

B represents a member having beveled upper and lower edges partially cylindrical in its widest portion and having straight flat extensions rounded at their outer ends, as seen most clearly in Figs. 1 and 2. The cylindrical portion of the member B is united with the 30 long side of the member A by two cylindrical members C and C'.

The essential features of the design are the partially-cylindrical member B, with its flattened end portion, and the cylindrical members C and C', connecting the partially-cylindrical member B and the U-shaped member A.

35 What I claim is—

The design for a gun-carrier, substantially as herein shown and described. 40

In witness whereof I have hereunto set my hand in presence of two witnesses.

OLIVER THORN.
